MANUFACTURE OF FLOOR COVERINGS

Richard G. Knowland, Pelham, N. Y., assignor to
 Bigelow-Sanford Carpet Co. Inc., Thompson-
 ville, Conn., a corporation of Massachusetts

Application January 25, 1936, Serial No. 60,823

7 Claims. (Cl. 28—1)

This invention relates to the manufacture of floor coverings, and particularly to a novel method of forming the heading between adjacent rugs which are woven or otherwise fabricated in a connected series and also to a method of separating and binding the ends of individual rugs which have been so constructed.

It has been common heretofore to weave rugs in an elongated series, each rug being joined to the next succeeding rug in the series by a so-called heading, formed by continuing the weaving of the backing fabric while omitting the formation of pile tufts. After a large number of rugs have so been woven in series, the individual rugs are cut apart by severing the heading, after which the portions of heading protruding from both ends of each rug are bent back and secured to the undersurface of the rug as by stitching or other suitable means. If desired, a fringe may be attached to the bent-back heading to enhance the appearance of the rug.

Such common methods of finishing the ends of rugs woven or otherwise fabricated in series are objectionable in that they produce a bulky ridge at the end of the rug conducive to undue wear and presenting a dangerous condition to one stepping onto the rug. It has been proposed heretofore to remedy these objectionable features by the elimination not only of the pile yarns in the heading as has been common, but also by the elimination of the weft threads of the heading, leaving the individual rugs connected together merely by unwoven warp threads. The individual rugs are thereafter cut apart by severing through the unwoven warp threads which are subsequently bent back and secured to the undersurface of the rug backing, the purpose being to reduce the bulky ridge at the end of the rug by such elimination of the weft threads.

I have found that whereas the elimination of weft threads is effective to reduce bulkiness, yet a heading composed merely of unwoven warp threads does not bind the end wefts and tuft rows sufficiently to hold them during the finishing operations to which the rugs are subjected while still connected end to end. A heading composed merely of unwoven warps is not easily cut.

It is the primary object of the present invention to improve on prior methods of this character by not only eliminating bulkiness in the turned-back heading through the elimination or subsequent removal of weft threads therein, but also by securing, while the rug is still in the loom or other fabricating mechanism, the unwoven warp threads, the end rows of pile tufts and the

weft threads of the backing immediately adjacent the heading, thereby eliminating all tendency of the component elements of the rug to loosen up during the subsequent finishing operations. It is my further purpose to provide a method in which the securing medium employed produces a composite heading which not only may thereafter readily be severed for cutting the rugs apart, but which also itself possesses adhesive properties by which the severed heading may be secured to the undersurface of the rug without further application of adhesive and without stitching.

These and further objects and advantages of my invention will appear from a more detailed description thereof taken in connection with the accompanying drawing, in which—

Fig. 1 is a perspective view of a portion of a series of rugs at the stage of a typical weaving operation at which my novel securing medium may be applied;

Fig. 2 is a diagrammatic plan view illustrative of the steps in my novel method prior to the severing of the series into individual rugs;

Fig. 3 is a sectional view taken lengthwise of a series of rugs showing the unwoven warps of the heading after the treatment indicated in Fig. 2, and I have indicated in dotted lines, the manner of severing the heading;

Fig. 4 is a detail longitudinal section of the heading of a single rug after the severing, indicating the manner in which the composite heading formed by my novel method is secured to the undersurface of the rug;

Fig. 5 is a plan view of a modified method of forming the heading, and

Figs. 6 and 7 are views of the undersurface of a rug indicating my method of securing, to the backing fabric, the heading of Fig. 5.

As stated above, it is common to form the heading between adjacent rugs woven in a connected series, by omitting the pile tufts during a predetermined length of weaving of the backing material to present an untufted area of material at which the rugs may be cut apart. In accordance with the preferred embodiment of my invention, not only the pile tufts, but also the weft threads of the backing material are omitted between adjacent rugs. This may be accomplished in any suitable manner, such as by interruption of the needle or shuttle mechanism for a brief interval during which the rug is advanced by the take-up roll. As indicated generally at A in Fig. 1, the pile areas 1, 2 and 3 defining a plurality of individual rugs fabricated in a connected series, may be woven on a loom of any suitable

type, having the reed indicated diagrammatically at 5 and the shed forming heddles indicated at 6. A take-up roll 7 is provided, as is customary, for intermittently advancing the series of rugs 5 through the loom and over the breastplate 8. The heading 10 separating the adjacent rugs 2 and 3, which is enlarged somewhat in the drawing for clarity of illustration, comprises, as indicated, a plurality of warp threads formed by 10 continuing the feeding of the warps of the backing fabric by the take-up roll 7 while interrupting both the needle or shuttle mechanism employed to insert the wefts of the back fabric and also the pile tuft forming mechanism such as the pile 15 wires, tube frames or the like. Although my invention is particularly adapted for use in connection with weaving on Axminster looms, yet it is also effective when used with other types of weaving, as well as in the fabrication of rugs 20 without weaving, and it will be noted that in certain types of looms the unwoven heading 10 will include not only the extended warps of the backing fabric, but will also include a continuation 25 of the pile warps.

25 After the desired length of unwoven warp threads has been provided by suitable advancement of the take-up roll 7, the weaving of the next rug 3 of the series is commenced by starting the mechanism to insert weft shots and to form 30 the pile area. After the weaving of the pile area 3 has commenced and while the heading 10 is still on the breastplate 8, the securing medium 11 is applied. For this purpose the loom may be stopped if necessary, but I have found that the 35 breastplate is sufficiently extensive and the feeding of the rugs by the take-up roll 7 sufficiently slow during the weaving, to permit the operator to position and lightly secure the strip 11 over the unwoven warp 10 without interrupting the 40 weaving operations.

The securing medium 11 preferably comprises a thin strip of rubber of a length approximately equal to the width of the rugs, and of a width approximating the length of the unwoven warps 45 10, whereby the strip fits snugly between the edge rows of pile tufts 12 and 13 of the rugs 2 and 3, for example, as indicated in Fig. 1.

Prior to the superimposing of the binding strip 11 over the unwoven warps, I preferably apply 50 to the undersurface of the strip, a thin film 15 of adhesive for temporarily securing the rubber strip 11 in position.

Thereafter, and prior to cutting the rugs apart, the rugs are subjected to the common 55 finishing operations which include the passage of the connected series of rugs through a heating chamber 20 (Fig. 2) for applying heat to the rugs in the customary manner. It will be observed that during these various well-known 60 operations which need not be described in detail herein, the end rows of pile tufts 12 and 13 of adjacent rugs are maintained in their tightly woven position as a result of the abutting relation of the side edges of the reinforcing strip 11 65 with the end rows of tufts.

As indicated in Fig. 3, the application of heat to the rugs during the finishing process causes the rubber strip 11 to soften considerably and to flow somewhat downwardly and between the adjacent unwoven warp threads, whereby not only to embed the major portion of the warps in rubber, but also to surround the weft shots 21 and 22.

After the rubber has cooled, the composite 75 heading which is thus formed with unwoven

warp threads embedded in rubber, is cut apart as indicated at 19 by severing mechanism commonly employed for such purposes, to separate the individual rugs, thereby forming the heading sections 25 and 26 for binding up the ends of 5 the individual rugs. After the rugs have thus been cut apart, the composite heading for one of the rugs, such as is indicated at 25 in Fig. 4, is bent back in position contiguous to the undersurface of the backing fabric 30 of the rug and 10 is then again subjected to heat in any suitable manner such as by the application of a hot iron as indicated at 35, to cause the rubber 11 again to become plastic and to flow into the backing fabric 30 thereby further to embed the unwoven 15 warp threads 10, and also to surround and secure the warp threads 31 of the backing fabric and the end weft shots 32 thereof.

During this application of heat, I preferably also apply pressure to force the plastic rubber 20 well into the interstices of the backing fabric and, as indicated somewhat enlarged at 25a, this application of heat and pressure also materially reduces the thickness of the composite heading which is thus secured to the undersurface of the rug, so that no bulky ridge is presented. It is apparent that if it is desired to add a fringe to the rug for the purpose of giving the rug a more dressy appearance, such fringe may readily be adhered to the composite heading after 30 the same has been bent back in the position indicated in Fig. 4 and prior to the application of heat and pressure by the iron 35.

Referring now to Figs. 5, 6 and 7, I will describe a modification of my novel method wherein 35 the medium employed to form a composite heading with the warp threads for securing the warp threads of the heading, the end weft shots of the backing fabric and the end rows of pile tufts and also to furnish an adhesive agency for securing the severed heading to the undersurface of the rug backing, comprises weft threads composed of a substance which I shall designate as a potential adhesive and which may subsequently be rendered plastic by the application of a suitable 45 softening agent such as heat or a solvent.

As indicated in Fig. 5, the pile areas 50 and 51 of a pair of adjacent rugs of a woven series are separated by a heading, indicated generally at 55, and comprising, as before, the warp threads 56 50 which may be a continuation between the rugs of the warp threads of their respective backing fabrics. In constructing a rug in accordance with my modification, however, the rubber strip 51 is omitted, and in place thereof a plurality of 55 weft threads 57 of special characteristics are woven through the warp threads 56. The weft threads which I employ are composed preferably entirely of a substance which may be rendered plastic by the subsequent application of a suitable 60 softening agent. As an example of a thread which is suitable for this purpose, I may employ spun fibres of cellulose acetate, which may thereafter be completely dissolved by the use of a suitable solvent such as a mixture of 95% ethylene 65 dichloride and 5% ethyl alcohol. If desired, I may employ a thermo-plastic yarn, composed of 15 parts chlorinated rubber, 10 parts resin, and 10 parts dibutyl phthalate. A thread of these characteristics is woven into the warp yarns of 70 the heading in place of the weft threads customarily employed in the backing fabric, and by providing a fairly close weave of these yarns I effectively secure not only the warp threads of the heading, but also the component elements 75

of the rug itself, such as the weft yarns of the 5
backing fabric and the pile yarns forming the
end rows of pile tufts so that those elements are
not loosened during the subsequent treatment of
the rug. If this subsequent treatment involves
the application of heat, as frequently, it is
preferable to employ a weft thread which is
solvent-plastic rather than thermo-plastic.

After a series of rugs have so been woven and
10 treated, if desired, but while the weft threads 57
are still in a non-plastic condition, the individual
rugs are separated by cutting through the com-
15 posite heading separating adjacent rugs, as be-
fore. The fabric which constitutes the composite
heading, formed by the combination of the ex-
tended warp threads of the backing fabric and
the potentially plastic weft threads, may readily
20 be severed as any piece of fabric is severed, and
thereafter the heading is bent back contiguous
to the undersurface of the fabric in the customary
manner, and as illustrated at 60 in Fig. 6.

Thereafter, the heading portion 60 is subjected
to whatever treatment is necessary to render
plastic the weft threads 57, depending upon the
25 characteristics of the yarn employed, such as by
treatment with heat, or with a suitable solvent as
indicated above and as illustrated in Fig. 7. The
effect of such treatment is to convert the weft
threads, preferably completely, into a plastic ad-
hesive medium, which flows into the interstices
30 of the backing fabric, and not only effectively
secures the warp threads 55 of the heading thereto,
but also further secures the warp threads and
the end weft shots of the backing fabric as well
35 as the end rows of pile tufts.

Obviously, the potentially adhesive medium may
be incorporated into the warp threads of the
heading otherwise than in sheet form in accord-
40 ance with the preferred embodiment of my in-
vention, or in thread form in accordance with my
modification, such as by treatment of the warp
yarns themselves or by employing a weft yarn
which carries an adhesive coating but I prefer
45 to use a medium which not only binds the com-
ponent parts of the rug during the finishing
operations prior to cutting the composite heading,
but which also leaves a severed heading se-
cured to the backing fabric in which the weft
50 threads have either been omitted or subsequently
removed.

Although I have illustrated in the drawing a
typical two-shot Axminster fabric, it is obvious
that my invention may as effectively be em-
ployed with a three-shot or other Axminster
55 weave as well as with weaves which are not of
the Axminster type. Nor is my invention to be
limited to use in connection with rugs fabricated
by weaving of any sort. Thus, where a rug is
constructed by securing, by adhesives or other-
60 wise, a pile area onto a prefabricated backing
such as burlap, or the like, the backing may be
woven in strip form having a plurality of rug
areas separated by warps which are either un-
woven or are interwoven with potentially adhesive
65 weft threads. After the pile tufts have been
inserted on the backing fabric so constructed,
the rubber strip element 11 may be secured in
place, and treated as before, or if potentially
adhesive weft threads have been employed, a plas-
70 ticizing agent is subsequently applied as before.
I do not wish to limit myself in such details ex-
cept as indicated in the appended claims.

I claim:

1. The method of making floor coverings which
75 comprises constructing a plurality of pile areas

connected end to end by a heading consisting of
unwoven warp threads, binding together the warp
threads by securing thereto a sheet of thermo-
plastic material, separating adjacent floor cover-
ings by severing simultaneously the heading and
the thermo-plastic material, bending back the
severed heading and thermo-plastic material and
applying heat thereto to secure the bent back
heading to the undersurface of the backing
fabric.

2. The method of making floor coverings which
comprises constructing a plurality of pile areas
connected end to end by a heading consisting of
unwoven warp threads, binding together the heading
by applying to the warp threads a sheet of 15
thermo-plastic material, applying heat to the
thermo-plastic material to render the same plas-
tic and embed unwoven warp threads therein,
separating adjacent floor coverings by severing
simultaneously the heading and the thermo- 20
plastic material, bending back the severed heading
and thermo-plastic material and applying
heat thereto to secure the bent back heading to
the undersurface of the backing fabric.

3. The method of making floor coverings which
comprises forming a pile area on a backing fabric
composed of warp and weft yarns, extending the
warp yarns of the backing fabric beyond the pile
area so formed to connect the same to the pile
area of the next succeeding floor covering, said 30
connecting portion being devoid of pile, binding
together the extended warp yarns by securing
thereto a potentially adhesive medium forming
with the warp yarns a composite heading extending
between adjacent floor coverings, separating 35
the individual floor coverings by severing the
composite heading so formed, bending back the
severed heading and treating the potentially ad-
hesive medium in the heading to secure, adhe-
sively, the warp yarns to the undersurface of the 40
backing fabric.

4. The method of making floor coverings which
comprises forming a pile area on a backing fabric
composed of warp and weft yarns, extending the
warp yarns of the backing fabric beyond the pile 45
area so formed to connect the same to the pile
area of the next succeeding floor covering, said
connecting portion being devoid of pile, binding
together the extended warp yarns by applying
thereto a thin strip of rubber material disposed
contiguous to the end rows of pile tufts of the
successive pile areas, heating the rubber material
to render the same plastic whereby to embed the
warp yarns in the rubber material, separating the
successive floor coverings by severing the warp 55
yarns so embedded, bending back the embedded
warp yarns and securing the same to the under-
surface of the backing fabric by again applying
heat to the rubber material.

5. The method of making floor coverings which
comprises forming a pile area on a backing fabric
composed of warp and weft yarns, extending the
warp yarns of the backing fabric beyond the pile
area so formed to connect the same to the pile
area of the next succeeding floor covering, bind-
ing together the extended warp yarns by weaving
into the extended warp yarns potentially adhe-
sive weft yarns to form a continuous fabric ex-
tending between successive rugs and binding the 70
end weft shots and end rows of pile tufts in each
rug, separating the rugs by severing the con-
necting fabric, bending back the severed fabric
and securing the severed portions to the under-
surface of the backing fabric by treating the 75
75

potentially adhesive weft yarns to liberate an adhesive.

6. The method of binding the weft-wise cut ends of pile floor coverings, which comprises weaving a length of fabric with the pile tufts therein, providing a length of material without tufts and then continuing to weave the fabric with tufts to provide a second length of woven tufted fabric and to leave between the two woven tufted portions a length of untufted material containing warp threads, applying to said length of untufted material while under tension a potentially adhesive medium, cutting weft-wise the material between the tufted portions thereby leaving a length of untufted material extending beyond the edge of the adjacent tufted portion, folding said last named length of untufted material about the bottom of such adjacent portion of tufted material, treating said potentially adhesive medium to render it actively adhesive and

adhering the length of untufted material containing such adhesive to the back of the adjacent portion of tufted material.

7. The method of making floor coverings which comprises forming a pile area on a backing fabric composed of warp and weft yarns, extending the warp yarns of the backing fabric beyond the pile area so formed to connect the same to the pile area of the next succeeding floor covering, said connecting portion being devoid of pile, and binding together the extended warp yarns by securing thereto a potentially adhesive medium forming with the warp yarns a composite heading extending between adjacent floor coverings, whereby the end weft shots and end rows of pile tufts of the successive pile areas are secure while the floor coverings are being subjected to the finishing operations.

RICHARD G. KNOWLAND. 20
